UNITED STATES PATENT OFFICE

125,877

DESIGN FOR A BELT

Marian Halstead Taft, Washington, D. C.

Application December 4, 1939, Serial No. 88,682

Term of patent 3½ years

To all whom it may concern:

Be it known that I, Marian Halstead Taft, a citizen of the United States and a resident of Washington, in the District of Columbia, have invented a new, original, and ornamental Design for a Belt, of which the following is a specification, reference being had to the accompanying drawing, forming a part thereof,

In the drawing:

I claim:

The ornamental design for a belt, substantially as shown.

MARIAN HALSTEAD TAFT.
